UNITED STATES PATENT OFFICE.

CHARLES C. PLAISTED, OF CHICOPEE, MASSACHUSETTS.

BIT-BRACE FOR BORING OBLIQUELY TO THE AXIS OF THE STOCK.

Specification of Letters Patent No. 17,891, dated July 28, 1857.

To all whom it may concern:

Be it known that I, CHARLES C. PLAISTED, of Chicopee, in the county of Hampden and State of Massachusetts, have invented an 5 Improvement in Bit-Stocks; and I do hereby declare that the following is a full and exact description thereof, reference being had to the accompanying drawings and to the letters and figures marked thereon.

10 Figure I, view of the exterior of the instrument; Fig. II, same, in position for boring oblique holes; Fig. III, longitudinal section of joint and connections; Fig. IV, same in oblique position; Fig. V, collars, connecting-link, and handle; Fig. VI, plan and section of the upper cylinder; Fig. VII, plan and section of the lower cylinder.

This instrument can be used in the same manner as the bit-stock in common use, and 20 is also intended for boring holes that are at the junction of two planes or close to the corner of the walls of a room where there is not sufficient space to allow the common bit-stock to be turned, as is often required to be 25 done for bell-wires, gas fixtures, &c. To effect this I employ a universal joint, which occupies a position between the bit-socket and the stock, its construction being as described below, the main features of the invention consisting in the united action of the 30 collars, the universal joint, the connecting link and handle.

The bow or crank S, Figs. I and II, is made in the usual manner, having a loose knob or 35 bearer T, at the top. The collars A and B are fitted to the upper and lower parts of the universal joint R, R', R'' in such a manner as to allow a free motion of these parts, while they serve as bearings for them; the connecting-link C prevents them from moving 40 around in the bit.

The link C, has a slot U at the end where it is fastened to the upper collar A, by the 45 screws D, D', and as the brace is inclined, more or less, the slot U traverses upon the pins or screws D D', the lower end of the link C making a partial revolution at the same time upon the pins or screws E E', which are attached to the lower collar B. The link C 50 is curved to suit the collars, a part of it being cut out, as shown in Fig. V, to allow the handle F to be closed or shut into it.

The handle F is fastened, near its lower end, by the pin G to the link, and has, near the same point, a protuberance with a flattened face, as at V, Fig. IV, by means of which, the cylinder H retains the handle F in its closed position when required.

The cylinder H, incloses the upper part of the universal joint R R' and when the brace 60 is in the position shown in Fig. I, it rests upon the lower collar B and can not move from this place. The cylinder has upon the inside two grooves, one of them X, Fig. VI, parallel with its axis, the other W, concentric. The cylinder H is kept in its proper place by the projecting stud K, Figs. III and IV which fits the circular groove W. By moving the cylinder H until the stud K passes into the longitudinal groove X the 70 downward motion of the cylinder is effected.

It will be observed that the surface of the cylinder H is at one side for its whole length flattened; this flattened side is, (during the sliding down of the cylinder), toward the 75 handle F; it touches the lower end of it, by passing on the corresponding flattened surface V of said handle F, and holds it parallel to the axis of the brace, and within the connecting link C.

The cylinder M, inclosing the bit-socket has an eccentric groove N, its outer circumference nearly touching the inside of the cylinder at one point, while the opposite point opens in the outer circumference of the cylinder, as shown in Fig. VII. In setting the cylinder on the lower part R'' of the universal joint, the spring and latch P is kept close to that part until it falls into the groove N; on giving the cylinder M a turn, the latch 90 P enters the groove N, and as the latch projects at right-angles to the spring both to the right and left, its projections hold the cylinder M, and also the bit which is provided, as usual, with a notch near its end.

A steady-pin J, is fastened to the part R'' and enters the groove in the cylinder H, thus giving greater stability to these parts.

When the cylinder H, is in contact with the collar B, the axes of rotation of the bit, the socket, and the stock are in the same line.

What I claim is—

1. A bit-stock in which the socket or part

that holds the bit revolves about its axis in an oblique position with reference to the stock by means of the universal joint, or its equivalent, and the adjustable connecting-link extending from the socket to the stock.

2. In combination with the above, I claim the cylinder or coupling by which the

axes of the bit and the stock are placed and retained in line with each other.

CHARLES C. PLAISTED. [L. S.]

In presence of—

WARREN SMITH,
MAX S. I. WILDE,
